UNITED STATES PATENT OFFICE.

MAXIMILIAN CHARLES SCHWEINERT, OF WEST HOBOKEN, AND JULIUS VOLCKHAUSEN, OF WEEHAWKEN, NEW JERSEY, ASSIGNEES TO A. SCHRADER'S SON, INCORPORATED, OF BROOKLYN, NEW YORK, A CORPORATION OF NEW YORK.

DUST-CAP.

1,302,441.

Specification of Letters Patent. Patented Apr. 29, 1919.

Application filed March 21, 1916. Serial No. 85,623.

To all whom it may concern:

Be it known that we, MAXIMILIAN CHARLES SCHWEINERT and JULIUS VOLCKHAUSEN, both citizens of the United States of America, residing in West Hoboken, in the county of Hudson and State of New Jersey, and Weehawken, in the county of Hudson and State of New Jersey, respectively, have invented certain new and useful Improvements in 10 Dust-Caps, of which the following is a specification.

This invention relates to dust caps for tire valves or the like, and aims to provide certain improvements therein.

15 The invention is particularly directed to a dust cap formed in two parts, one of which comprises the body of the cap and the other of which is a threaded bushing, which is designed to screw on the projecting end of the 20 valve casing. According to the preferred form of the invention the body of the cap is formed of approximately cylindrical shape and the bushing has a similar formation, inter-engaging projections being provided 25 on the bushing and cap whereby a firm and rigid connection may be made between the two. Preferably the bushing is formed with a slight taper, being narrower at its outer end, and the cap body is swaged or spun 30 down to engage such tapered portion, whereby any relative longitudinal movement is prevented. The invention also includes certain other features of improvement which will be hereinafter more fully described.

35 Referring to the drawings,—

Figure 1 is an elevation of the preferred form of cap.

Fig. 2 is a similar view to Fig. 1 on an enlarged scale, the lower part of the cap being 40 shown in diametrical section.

Fig. 3 is a cross-section on the line 3—3, Fig. 2.

Fig. 4 is a similar section on the line 4—4, Fig. 2.

45 Fig. 5 is an elevation of the bushing.

Referring to the drawings, let A indicate the cap as a whole. It preferably comprises a body portion B and a bushing C. The body portion is usually closed at its top and open at its bottom, and constitutes the protecting inclosure for the valve casing. Such caps are usually constructed of brass largely for the reason that the screw-threaded portion of the cap is apt to rust if constructed

of steel. According to the present invention 55 the body portion may be conveniently formed of steel or other cheap metal, either galvanized, nickel-plated, or otherwise treated, to render it suitably rust-resisting, and the bushing or screw-threaded portion is 60 preferably formed of brass, so that there will be no danger of its rusting in place on the valve casing. Ordinary rust-resisting coatings when applied to a steel bushing or other screw-threaded part are found to be ineffectual, since they are subject to wear and the coating is quickly injured. The present construction cheapens the cost of production, since only a small portion of the more 65 expensive metal is used.

70 According to the present invention means are provided to secure a rigid connection between the body portion and bushing. To this end the body portion is formed with one or more recesses D (Fig. 3), while the bushing is formed with a projection or projections E, Fig. 5, designed to enter the recesses D and prevent relative rotative movement 75 of the parts. By reference to Figs. 1 and 2 it will be noted that the body of the cap is 80 formed with a series of flutes or ridges struck from the body of the metal and extending a substantial distance along the sides of the cap. This construction of cap is 85 an advantageous one in that it secures a large gripping surface by which the cap may be screwed on the valve casing. The present invention is particularly applicable 90 to this construction of cap, since the lower parts of the flutes on the interior present the necessary recesses D which are utilized to receive the projections E.

95 The bushing may be forced within the recesses to such an extent as to hold the bushing against longitudinal as well as rotative displacement, but we refer to so construct the parts that an additional means is provided for resisting such movements. To 100 this end the bushing is preferably tapered toward its lower end and the foot of the body portion is pressed or spun inwardly, as best shown in Fig. 2, thereby not only preventing the longitudinal displacement of the bushing, but clamping the latter against 105 rotative displacement. The bushing and cap body may be given other relative forms which will accomplish the result, but we prefer the tapered construction for the re-

son that it is easily manufactured, and for the further reason that the foot of the cap can thereby be made smooth and free from abrupt shoulders.

5 While we have shown and described the preferred embodiment of the invention, it will be understood that we do not wish to be limited thereto, since various changes may be made therein without departing from the 10 invention. It will also be understood that the invention is applicable to other devices than dust caps.

What we claim is:—

1. A drawn-metal dust cap for tire valves 15 or the like, having a substantially cylindrical body portion, and a substantially cylindrical bushing inserted within the open end of the cap, the body portion having a recess formed by a flute or corrugation, and 20 the bushing having a coöperating projection adapted to secure non-rotative connection between the body portion and bushing.

2. A drawn-metal dust cap for tire valves 25 or the like, and a brass bushing inserted in the open end thereof, the cap having a recess formed by a flute or corrugation, and

the bushing having a projection coöperating with said recess to prevent relative rotation of the parts, and the cap being pressed in to overlie the bushing and prevent longitudinal separation of the bushing and cap. 30

3. A dust cap for tire valves or the like, having a body portion which is substantially cylindrical and having a series of flutes adapted to constitute a grasping portion, 35 and means for securing said cap to a threaded valve casing or the like comprising a bushing also substantially cylindrical in form, said bushing being inserted in the open end of the cap, and having projections 40 entering the recesses of said flutes, and said parts having means for preventing relative longitudinal displacement.

In witness whereof, we have hereunto signed our names in the presence of two sub- 45 scribing witnesses.

MAXIMILIAN CHARLES SCHWEINERT.
JULIUS VOLCKHAUSEN.
